PHONOGRAPH

Thomas C. Brown, San Francisco, Calif., assignor
to Thomas A. Edison, Incorporated, West
Orange, N. J., a corporation of New Jersey

Application July 12, 1932, Serial No. 622,054

13 Claims. (Cl. 274—21)

This invention relates to phonographs and more particularly to improvements in the means for effecting and controlling the operation of the back-spacing mechanism in commercial phonographs or dictating and transcribing machines. Such phonographs will hereinafter be generally referred to as dictating machines.

A dictating machine is ordinarily provided with mechanism whereby the sound box may be back-spaced at the will of the user, in order to reproduce or repeat the reproduction of any desired portion or portions of the matter recorded on the record tablet or cylinder. Mechanisms of this general character are disclosed in the Holland 10 U. S. Patent No. 1,275,257, granted August 13, 1918, and the pending U. S. application of Gramann, Serial No. 375,367, filed July 2, 1929, now Patent 1,979,829, granted November 6, 1934. The present invention is applicable to such 15 mechanisms, its purposes being somewhat similar to those of the invention disclosed in my co-pending application Serial No. 588,274, filed January 23, 1932.

The principal object of the invention is to provide an improved construction for enabling successive operations of a back-spacing mechanism to be effected upon a single actuation of a control key or other device.

A further object of this invention is to provide 20 a construction comprising means for interrupting an electrical circuit which includes an actuating device for the back-spacing mechanism of a phonograph, which means is also adapted and arranged to tension the belt of the phonograph 25 motor.

Further objects and features of the invention will appear more fully in the following specification and appended claims.

For a clearer understanding of my invention, 30 attention is directed to the accompanying drawings, wherein:

Figure 1 is a view in end elevation, partly broken away, of a dictating machine, having a preferred embodiment of my invention applied thereto;

Fig. 2 is a plan view, partly broken away, of the machine shown in Fig. 1;

Fig. 3 is an enlarged view in side elevation, partly in section, of the sound box carriage and some of the structure, including the back-spacing mechanism, associated therewith.

Fig. 4 is a part sectional view taken on line 4—4 of Fig. 3;

Fig. 5 is an enlarged elevational view of the device shown in Fig. 1 for causing repeated operations of the back-spacing mechanism;

Fig. 6 is a sectional view taken on line 5—5 of Fig. 5;

Fig. 7 is a circuit diagram of the arrangement for controlling and actuating the back-spacing mechanism; and

Fig. 8 is a fragmentary sectional view of the circuit interrupting means of the device shown in Figs. 5 and 6.

Referring to the drawings, and particularly to Figs. 1 and 2, the phonograph illustrated has a 10 base plate 1 which is supported on a suitable cabinet 2. The base plate 1 is provided adjacent its ends with spaced standards 3 and 4 which support several rods, among which are the front and rear guide rods 5 and 6. A carriage or arm 15 7 is slidably mounted on rods 5 and 6 and carries a sound box 8 having a stylus arm 9 which is provided with a stylus 10 (Fig. 3). In the normal operation of the machine, the stylus 10 is engaged with the surface of a cylindrical record 20 tablet A so as to track the record grooves of said tablet. The tablet A is mounted upon a conventional mandrel 12 for rotation therewith, said mandrel being secured to a rotatable shaft 12' mounted in a suitable bearing carried by plate 1. 25 A feed screw 13, supported at its ends in suitable anti-friction bearings 13' carried by the standards 3 and 4, is adapted to engage suitable means for causing feeding movement of the carriage or arm 7 in one direction along the rods 5 and 6. 30 The feed shaft or screw 13 is rotated by means of a gear 14 secured thereto and a smaller gear 15 secured to the mandrel shaft 12' and meshing with said gear 14.

The mandrel shaft 12' is adapted to be rotated 35 by means, of conventional form, comprising an electrical motor 16 which is suspended from the base plate 1 within the cabinet 2. The motor 16 has a driving pulley 17 which is engaged by a belt 18. This belt also passes over a larger pulley 19 which is rotatably mounted on a stub shaft 20 supported in the standard 4 in alignment with the mandrel shaft 12'. Through a suitably controlled clutch comprising the members 21 and 22, the rotation of the pulley 20 is adapted to be 40 45 transmitted to the mandrel shaft 12'.

In order to prevent motor vibrations and extraneous noises from being transmitted to the delicate sound box and associated means, the driving motor 16, as is customary, is suspended 50 from the plate 1 by means of coil springs, such as shown at 22 in Fig. 1. Because the motor is thus resiliently supported from the plate 1, it is necessary in order to maintain uniform frictional engagement of the belt 18 with the pulleys 17 55

and 19, to provide tensioning means for said belt. This means, in the present instance, comprises an idler pulley 23 rotatably mounted on a stud 24 which is secured to the free end portion of a swinging arm 25. This arm 25 is pivoted at 26 to the motor frame 16' and is urged in a counter-clockwise direction by a coil spring 27. Thus the belt 18 is at all times properly tensioned on the pulleys 17 and 19. I utilize this construction, comprising the idler pulley 23, to perform a novel function, as will be hereinafter more fully described.

The mechanism for back-spacing the carriage 7 is adapted to be operated by means including the rear guide rod 6 which is mounted in the standards 3 and 4 for turning movement. This mechanism comprises a U-shaped member 30, best shown in Figs. 2 and 4, pivotally mounted on a bushing 31 which is supported for sliding movement on the rod 6. The bushing 31 is firmly secured in spaced projections 32 and 33 of the carriage 7. The U-shaped member consists of the two spaced arms 34 and 35 and a base 36 and is mounted on the bushing 31 in the space between the said projections 32 and 33. The base 36 of the U-shaped member is angular as shown in section in Fig. 3, and supports a shouldered bolt 37 which extends forwardly therefrom. A long sleeve 39 is rotatably mounted on the bolt 37 and has a gear 38 secured thereto. Also secured to the sleeve 39 at its forward extremity is a worm wheel 40. Loosely mounted on the bushing 31, within the U-shaped member 30, is a cam 41 carrying a pin 42 which extends through a circumferential slot 43 in the bushing 31 and into a longitudinal slot 44 provided in the guide rod 6 and extending throughout its length. A pawl 45 is pivotally mounted on the cam 41 by means of a shouldered screw 46, and is spring-biased to engage a ratchet wheel 47 which is rotatably mounted on the bushing 31. A worm 48 loosely mounted on the bushing 31, is secured to said ratchet wheel and engages the gear 38.

The U-shaped member 30 and the parts carried thereby are normally urged in a counter-clockwise direction (referring to Figs. 3 and 4) by a leaf spring 50. This spring is fastened to the end portion 33' of the projection 33 and extends forwardly to engage and press downwardly upon a rod 51 carried at the forward ends of the arms 34 and 35 of the U-shaped member 30. Consequently the worm wheel 40 is normally constantly maintained in engagement with the feed screw 13. In the normal operation of the machine, the worm wheel 40 therefore coacts as a feed nut, with the feed screw 13 to advance the carriage lengthwise of the mandrel 12.

An arm 53 is clamped to the rockable rod 6 adjacent one end thereof, and a link 54 is pivotally secured at its ends respectively to the outer end of arm 53 and to the U-shaped armature 55 of an electromagnetic operating device. This device, in addition to the armature 55, comprises a coil 56, a core 57 and a frame 58 on which said core is supported and on which the armature 55 is also pivotally mounted at 59, as shown in Figs. 1 and 2.

The operation of the back-spacing mechanism supported by the carriage 7, is as follows: When the coil 56 of the electro-magnetic operating device is energized, the armature 55 is attracted by the core 57, and thereupon through the link 54 and arm, rocks the rear rod 6 through a small arc in a counter-clockwise direction (Fig. 1). Since the end of pin 42 is engaged with

the slot 44, the cam 41 to which this pin is secured, is thereupon turned (referring to Fig. 3) in a clockwise direction. The cam 41 through the pawl 45, then imparts a slight rotary movement to the ratchet wheel 47 and consequently to the worm 48. This worm in such rotary movement thereof, imparts a turning movement to the gear 38, sleeve 39 and worm wheel 40, whereupon the said worm wheel 40 rolls backwardly along the feed screw 13 which then co-acts therewith as a rack. A back-spacing movement of predetermined extent is thus given to the carriage 7. The cam 41 in the rotary movement thereof described, also actuates the spring-pressed pivoted arm or lever 30' so as to effect the centering of the stylus 10 with respect to the sound box 8 substantially at the completion of the back-spacing movement of the carriage, as described in detail in the co-pending application of H. F. M. Gramann, Serial No. 375,367, filed July 2, 1929. Upon de-energization of coil 56, the armature 55 returns to its original position (see Fig. 1) and through the link 54 and arm 53, turns rod 6, cam 41 and pawl 45 in a direction opposite to that described above. The worm wheel 40 remains locked in the angular position to which it was moved during the back-spacing operation and is ready again to act as a feed-nut for advancing the carriage, provided no further back-spacing is desired. Also the pawl 45 is now positioned to engage another tooth of the ratchet wheel 47 in preparation for a further back-spacing operation. For a more complete description of the construction and operation of the back-spacing mechanism, reference may be had to the Gramann application referred to above.

As hereinbefore set forth, one of the features of the present invention resides in an arrangement whereby the back-spacing mechanism can be operated repeatedly upon a single actuation of a control device. The arrangement herein shown for accomplishing this result will now be described.

The idler pulley 23 has an annular flange 65 for engagement by the belt 18, and disposed within this flange is a fairly thick disc 66 of insulating material (see Fig. 5). Disposed against the outer side of the disc 66 is a disc 67 of conductive material, which latter disc is secured in any suitable manner to the disc 66 and the pulley 23. Accordingly, when pulley 23 is rotated by the belt 18 during operation of the motor 16 the discs 66 and 67 are also rotated. Disc 67 is provided with a concentric opening or slot 68 (Figs. 5 and 8), which is filled by the insulating material of disc 66 so as to present a smooth surface flush with the outer face of disc 67. Located within the flange 65 adjacent its outer edge is a stationary disc 69 which is fastened to the arm 27 in any suitable manner and carries two terminal posts 70 and 71. A space 72 is provided between the discs 67 and 69, and within said space are two resilient wiping contacts 73 and 74, the contact 73 engaging the disc 67 at the same radial distance from the center of said disc as the center of the slot 68 and the contact 74 engaging the disc 67 at a considerably less radial distance so as to continuously have electrical contact with said disc in the rotation thereof. The wiping contacts 73 and 74 are respectively secured to the terminal posts 70 and 71 and are held in proper position by the engagement of their angular end portions 73' and 74' with openings 75 and 76 provided in disc 69. A suitable stiff conduit 78

(Fig. 1) may be provided below the plate 1 to guide the conductors 81 of the circuit of the coil 56 from a point adjacent said coil to a point near the pulley 23. The conductors 81 extend from the end of conduit 78 which is adjacent pulley 23 and are respectively secured to the posts 79 and 81.

The circuit of the coil 56 of the electro-magnet device for rocking rod 6 is controlled by a suitable switch or key 80 (Fig. 7). This circuit includes in addition to the coil 56 and switch 80, a suitable source of current 82, the contacts 73 and 74 and the disc 67, as clearly shown in Fig. 7. If the key 80 were depressed and no other circuit breaking means were provided, the armature 55 would be moved to a position opposite the core 57 and would be held in such position as long as the key 80 remained depressed. If the operator then desired more than one back-spacing operation it would be necessary to release the key 80 so as to deenergize the coil 56 and permit the armature 55 to resume its original position, under the action of gravity, and thereafter to press and release the key successively and repeatedly until the desired number of back-spacing movements would be effected. However, by the provision and arrangement of the circuit-controlling device comprising contacts 73 and 74 and disc 67, such operation of the key in order to obtain repeated back-spacing movements is rendered unnecessary. With this arrangement, it will be apparent that when the circuit of coil 56 is closed upon the depression of key 80 and the armature 55 is thereupon raised to a position opposite core 57 to thereby raise the link 54 and effect a back-spacing movement of the carriage 7, the slot 68 of disc 67 will, in the rotation of this disc, soon be brought to a position opposite the contact 73. Accordingly, after a short interval, due to the insulating material in said slot, the circuit of coil 56 will be opened. Immediately upon such opening of this circuit, the coil 56 will be de-energized and consequently the armature 55 and the mechanism associated therewith will fall back to their original positions, as shown in Fig. 1. However, in the continued rotation of disc 67 the slot 68 will soon clear the contact 73, and said disc will thereupon again establish electrical connection between the contacts 73 and 74 so that if the key is maintained depressed the circuit of coil 56 will again be closed and another back-spacing movement will be effected. Therefore as long as the key 80 is maintained depressed, successive back-spacing operations are obtained and the carriage 7 and sound box 8 are automatically returned step-by-step toward the beginning of the record.

It is to be understood that my invention is susceptible of embodiment in many other forms than the illustrative one herein shown and described, without departure from the spirit of the invention or the scope of the appended claims.

What I claim is:

1. In a phonograph having motive means for driving the same, a sound box carriage, means operable by said motive means for moving said carriage in one direction, back-spacing mechanism for moving said carriage in an opposite direction, means which includes a source of power and which is independent of said motive means for actuating and for supplying the energy to actuate said back-spacing means, and means comprising a device operable by said motive means for con-

trolling the actuation of said mechanism by said actuating means.

2. In a phonograph, a sound box carriage, driving means for moving said carriage in one direction, back-spacing mechanism for moving said carriage in a reverse direction, means which includes a source of power and which is independent of said driving means for actuating and for supplying the energy to actuate said back-spacing mechanism, and means comprising part of said driving means for controlling the actuation of said mechanism by said actuating means.

3. The combination with a phonograph comprising a sound box carriage, means for back-spacing said carriage, means comprising an electromagnetic device for actuating said back-spacing means, and a manually operable switch for the circuit of such electromagnetic device, of a movable device which is actuatable by the phonograph when the latter is in operation and which during such actuation thereof intermittently makes and breaks the circuit of said electromagnetic device, said movable device being independent of said switch.

4. The combination with a phonograph having means for driving the same, a sound box carriage, means comprising an electrical device and effective upon the closing of the circuit of said device to back-space said carriage a predetermined amount, and a manually operable switch for said circuit, of a device which is normally actuated by said driving means when the latter is operated to make and break said circuit intermittently whereby there may be intermittently imparted to said carriage a plurality of such back-spacings during a single closure of said switch.

5. The combination with a phonograph comprising a carriage, means for back-spacing said carriage, an electrical device operable when the circuit thereof is closed to actuate said back-spacing means, and a switch for said circuit, of means actuatable by the phonograph and independently of said back-spacing means, device and switch to make and break said circuit intermittently.

6. The combination with a phonograph comprising a movable sound box arm, back-spacing means for said arm, an electrical device for actuating said means, and a manually operable switch for the circuit of said electrical device, of a rotatable device which is actuated by the phonograph during operation of the latter and which acts automatically in its rotary movement to make and break said circuit intermittently.

7. A phonograph comprising a support, a rotatable mandrel mounted on said support, a motor for driving said mandrel, said motor being carried by said support in floating relation to said mandrel, a sound box carriage, means for back-spacing said carriage in respect of the mandrel, flexible power-transmitting means operatively connecting said motor and mandrel, a device for tightening said power-transmitting means, and means operable by said power-transmitting means through said tightening device for controlling said back-spacing means.

8. In a phonograph having a motor for driving the same, a sound box carriage, power-transmitting means comprising a belt associated with said motor, means comprising a rotary element for tensioning said belt, back-spacing mechanism for said carriage, and means actuated by said belt through said rotary element for controlling said back-spacing mechanism.

9. In a phonograph having motive means for

- driving the same and a mandrel, a feed screw and a sound box carriage all operable by said motive means, back-spacing means for said carriage, means independent of said motive means and
- 5 comprising an electro-magnet for operating said back-spacing means, a control switch in the circuit of said electro-magnet, and a switching device comprising a member operable by said motive means to make and break said circuit intermittently.
10. In a phonograph having motive means for driving the same, back-spacing mechanism, a device which includes a source of power and which is independent of said motive means for actuating and for supplying the energy to actuate said mechanism, and means operable by said motive means for controlling the actuation of said mechanism by said device.
- 15 11. In a phonograph having a motor for driving the same, a rotatable device associated with said motor and normally actuated during operation of the motor, back-spacing mechanism, means which includes a source of power and which is independent of said motor for operating and for supplying energy to operate said back-
- 20
- 25

spacing mechanism, and means actuatable by said device in its rotary movement for controlling the operation of said back-spacing mechanism operating means.

12. In a phonograph, a sound box carriage, a record support, means for driving said record support and for advancing said carriage in respect of the mandrel including a motor and flexible power-transmitting means cooperating with said motor, means for back-spacing said carriage, means independent of said motor for actuating said back-spacing means, and unitary means for tensioning said power-transmitting means and actuatable by the latter to control the operation of said actuating means.

13. In a phonograph having means including a flexible device for driving the same, a sound box carriage, means for back-spacing said carriage, means independent of said driving means for actuating and for supplying the energy to actuate said back-spacing means, and a device for tensioning said flexible device and actuatable by the latter to control the operation of said actuating means.

THOMAS C. BROWN. 25
